WATERPROOFED COMBAT VEHICLE

Arthur J. Scaife, Detroit, Mich.

Application March 15, 1944, Serial No. 526,623

3 Claims. (Cl. 180—1)

(Granted under the act of March 3, 1883, as amended April 30, 1928; 370 O. G. 757)

The invention described herein may be manufactured and used by or for the Government for governmental purposes, without the payment to me of any royalty thereon.

In military operations involving combat tanks, it is contemplated that the tanks shall be used in fording streams and shall at times become fully submerged. The object of this invention is to provide means for waterproofing a tank, especially when it is to be fully submerged. The major problems occur in connection with the intake of air and exhaust from the motor.

Many of the tanks now in use have a comparatively large intake opening at the top for ventilating the radiator. According to the invention, this opening is covered but is used, nevertheless, for circulating air through the radiator. The cover is in the form of a box, and a duct system is built around the face of the radiator. A conduit extends upwardly from the duct system and is connected to the box by a series of spaced ducts disposed outside of the body of the vehicle and thus subjected to water cooling. A circulating system is thus provided in conjunction with the usual radiator fan, and air is cooled in each circulation by the means described. Air is admitted into the vehicle in the first instance by a flexible tube extending therefrom and having its upper or intake end floated upon the surface of the water.

The exhaust pressure, when the motor is running, is sufficient to overcome the pressure of the water. However, in order to avoid back flow in the event the motor stalls, a check valve is provided on the outer end of the exhaust pipe. The valve is so designed that it will open under exhaust pressure against its weight and the pressure of the water. To accomplish this purpose, the outlet end of the exhaust pipe is disposed in an inclined plane and the valve has an overhead hinge axis so that it closes by gravity when the exhaust pressure drops.

An illustrative embodiment of the invention is disclosed in the following description and in the accompanying drawings in which:

Figure 1 is a side elevation of a military vehicle equipped according to the invention;

Figure 2 is a plan view thereof;

Figure 3 is a detail perspective view;

Figure 4 is a detail section of the exhaust valve, and

Figure 5 is a section on the line 5—5 of Figure 1.

In Figure 1 is shown a combat tank 1 of current design. The engine 2 is mounted in the rear, and behind the engine is a radiator 3. The

motor drives a fan 4 which throws air against and through the radiator in a manner well known in the art. The top of the tank is ordinarily formed with an opening 5 disposed above the motor and serving as the air intake. Normally, the opening 5 remains exposed, and the air admitted therethrough and passed through the radiator is discharged directly into the atmosphere.

The modifications made for the purpose of waterproofing the tank so that it may be submerged will now be described. The exposed crevices are first sealed with a plastic material or rubber. A box 10 is built around the opening 5 and is provided in its top with a hinged lid 11 which is water-tight when closed. The side wall structure of the tank extends rearwardly beyond the radiator by means of a wall member 12. A duct 13 is provided beneath the members 12 in sealed relation thereto and communicating with the space there-between. At the rear end of the duct 13 is mounted a substantially vertical conduit 14 communicating with the rear end of the duct along the width of the tank and extending upwardly beyond the top of the tank. The top 25 of the conduit is fitted with a cover 15 which forms a seal when closed.

The exposed upper forward wall of the conduit 14 is in constant communication with the rear end of the box 10 by means of a series of spaced conduits 17 extending lengthwise of the tank. The sloping end wall 18 of the tank extends from the duct 13 to the ducts 17 and joins the top 19 of the tank. The portions of the ducts 17 lying forward of the wall 18 have their intervening spaces 20 sealed by the top 19, while rearward of the wall 18 the spaces are not sealed and water is permitted to flow therethrough to the spaces 18 between the wall 18 and the conduit 14.

The lateral ends of the duct 13 are recessed or boxed inward to form exposed corner spaces 21 to accommodate the outlet ends of the exhaust pipes 22 extending from the motor 2. The exhaust pipes are extended laterally at 23 through the side walls 24 of the respective recesses and then prolonged lengthwise at 25 in the recesses and outside of the duct 13. On each pipe section 25 is attached an elbow 26 having its outer end 27 lying in a plane sloping upwardly and forwardly of the tank. To the upper portion of each elbow 26 is pivotally attached a yoke or hinge 28 carrying a disk 29 adapted to seat upon the end 27.

From the forward portion of the top of the

tank extends a flexible air tube 30 equipped at its free end with a float 31 having an intake opening 32. The air admitted to the tube 30 ventilates the crew compartment, and a portion thereof is directed to the carburetor. In the top of the tank is fitted an escape door 33 through which is formed a flooding opening 34. The latter is normally closed by means of a flooding valve 35 disposed and operable within the crew compartment. In the event that escape is necessary under water, the flooding valve is opened in order to equalize the water pressure on both sides of the door 33. An access panel 13' is removably held by latches 13a in the bottom of the duct 13.

In the operation of the device under water, the air admitted through the tube 30 is driven by the fan 4 through the radiator 3 and into the duct 13 and the conduit 14. From here it passes through the spaced conduits 17 into the box 5 and is recirculated by the fan. In passing through the conduits 17, the air is cooled by the water in the spaces 20, so that it is made effective for cooling the radiator 3 each time it is circulated.

The valve 29 normally closes the exhaust pipe by gravity and thus prevents water from backing up into the motor. The weight and effective surface of the valve are so determined with respect to the exhaust pressure that the latter will lift the valve when the motor is operating. If the motor stalls, the valve will close the exhaust pipe.

When the tank is operating on land, the air tube 30 may be readily detached at its coupling 36 to the tank. The covers 11 and 15 are swung over to open position by means of cables 37 attached to their free edges. The valve 29 is swung over upon the exhaust pipe and fastened thereto by a cord or wire, in open position.

While a specific embodiment of the invention has been shown and been described, it will be

understood that various alterations may be made without departure from the spirit of the invention as indicated by the appended claims.

What I claim is:

- 5 1. In a vehicle having an air opening in its top, a motor beneath said opening, a radiator adjacent to said motor, a fan driven by said motor and directed towards said radiator, an air duct over the face of said radiator and having an outlet below the radiator, a conduit extending upwardly from said outlet, a box mounted over and enclosing said opening, and spaced ducts connecting said conduit to said box and disposed outside of the vehicle.
- 10 2. In a vehicle having an air opening in its top, a motor beneath said opening, a radiator adjacent to said motor, a fan driven by said motor and directed towards said radiator, an air duct over the face of said radiator and having an outlet below the radiator, a conduit extending upwardly from said outlet, said conduit having an open upper end for discharging gaseous media when not submerged, means for sealing said open upper end of said conduit, a box mounted over and enclosing said opening, said box having an air intake for receiving ambient air when not submerged, a removable closure for sealing said intake, and spaced ducts connecting said conduit to said box and disposed outside of the vehicle.
- 15 3. In a vehicle having an air opening in its top, a motor beneath said opening, a radiator adjacent to said motor, a fan driven by said motor and directed towards said radiator, an air duct extending beneath said radiator, means forming a fluid connection between said duct and the face of said radiator, a conduit extending upwardly from said duct, a box mounted over and enclosing said opening, and spaced ducts connecting said conduit to said box and disposed outside of the vehicle.

ARTHUR J. SCAIFE.
